W. J. WILLIAMS.
RAIL TIE PLATE.
APPLICATION FILED DEO. 14, 1908.

921,044.

Patented May 11, 1909.

UNITED STATES PATENT OFFICE.

WILLIAM J. WILLIAMS, OF FRANKLIN, PENNSYLVANIA.

RAIL-TIE PLATE.

No. 921,044.

Specification of Letters Patent.

Patented May 11, 1909.

Application filed December 14, 1908. Serial No. 467,519.

To all whom it may concern:

Be it known that I, WILLIAM J. WILLIAMS, residing at Franklin, in the county of Venango and State of Pennsylvania, have invented a new and Improved Rail-Tie Plate, of which the following is a specification.

My invention is in the nature of an improved construction of rail tie plate, of that class that are made by the rolling processes and it has for its object to provide a tie plate for the purposes stated, of light weight, simple in construction and so designed as to have all of the desirable features of the more complicated forms of metal tie plates, without their attendant high cost of manufacture.

My invention, which in practice is rolled into shape by suitable means or otherwise made, comprehends generally a tie plate having pendent flanges for digging into the ties, a flat bearing face formed with the usual spike apertures, and having pairs of lugs for taking up the lateral rail strain in one direction, and relatively so disposed with reference to an intervening spike aperture, whereby to provide for a clamping engagement therewith of the opposite sides of the spike head when driven home and between the lugs and for holding the shank of the spike away from the rail base, so as to relieve the head end of the spike from being rubbed or crowded backwardly by lateral stress of the rail, and whereby the spike will be fixedly held from rattling movement, either in a direction parallel with the rail or at right angles thereto.

In its more subordinate features, my invention consists in certain details of construction and peculiar combination of parts, all of which will be hereinafter fully described, specifically pointed out in the appended claims and illustrated in the accompanying drawings, in which:

Figure 1, is a perspective view that illustrates the manner in which my improved plate is used. Fig. 2, is a vertical transverse section of the same, taken on the line 2—2 on Fig. 1. Fig. 3, is a detail perspective view of the plate. Fig. 4, is a detail perspective view of a portion of the plate having one set of rail end bearing and clamping lugs and a spike opening, and Fig. 5, is a detail cross section taken on the line 5—5 on Fig. 1.

In the practical embodiment of my invention, the tie plate is formed of a substantially thin top or bearing member 1, the up-

per face of which, except where it has the rail engaging lugs, presently referred to, is smooth throughout.

The under side of the plate has one or more (four being shown) pendent longitudinal tie engaging flanges 2—2, the outermost ones of which are at the opposite edges 10—10 of the bearing member 1 and the several flanges are preferably tapering or sharpened that they may conveniently penetrate the tie, the said member 1 also having the spike apertures 4 that are disposed between the flanges 2—2 and through which are driven the spikes that, together with the flanges 2—2, firmly hold the plate and the superimposed rail secured to the tie as will be clearly understood from Figs. 1 and 2 of the drawings.

3—3 designate lugs that are arranged in pairs and project upwardly from the plate 1. These lugs are formed on the plate top during the process of rolling the entire plate and my construction of plate is the product of the process or method of making the plates disclosed in my co-pending application filed May 22, 1908.

A pair of lugs 3—3 is disposed about each spike aperture at one end of the plate 1 with the adjacent side walls thereof spaced away from the said spike apertures and they and the spike apertures are relatively so positioned that the inner or straight impact edges 30 (being the edges that the base of the rail engages, see Fig. 2) are in a transverse plane a little in advance of the inner edge 40 of the aperture as best shown in Fig. 2, so that when the spike S is driven home the shank s will be slightly offset from the base flange of the rail, so as to relieve the spike of the lateral impact or strain from the rail, especially on curves, it being understood that since the lugs 3 are a little in advance of the edge 40 of the spike aperture, the said lugs take up all such strain.

To hold the spike from working loose laterally, the lugs 4 are spaced just enough to allow the spike shank to freely enter the spike aperture and so the opposite edges of the spike head will bind between the lugs, the adjacent inner faces of which are slightly beveled at the top to facilitate the binding or crowding action of the spike head when driven therebetween.

It is understood that in the practical application of my invention the precise number of lugs 3 and the pendent flanges 2 is imma-

terial as these may be varied to suit the character of the rail to be supported, but in every instance however the lugs are formed on the top of plate 1 in vertical alinement with the pendent flanges, there being one for each flange.

By reason of forming the plate in the manner shown and described, the thin parts of the plate between the lugs can be easily 10 punched for the spike holes, and furthermore it admits of making the plates economically and practically correct for immediate use as soon as they come from the pressing and hydraulic order provided.

Having thus described my invention, what I claim is:

1. A tie plate comprising a body portion having a plane upper face and a series of pendent tie engaging flanges, and spike openings, the latter being between the flanges, rail engaging studs on the upper face of the body portion, said studs being in vertical alinement with the flanges in the body, said studs being spaced to receive the head of the 25 spike tightly therebetween.

2. A tie plate combining the following elements, a body portion plane throughout, said body having a series of longitudinal pendent flanges, pairs of studs in one end of the tie 30 plate for engaging with the spike heads, and slots in the body portion disposed within the pairs of studs and with their front edge inside of the bearing faces of said studs.

3. A tie plate having upon its under side 35 one or more longitudinally disposed tie engaging flanges, said plate having a plane upper surface, studs arranged in pairs integral with and projected above said surface and in vertical alinement with the flanges and

spike slots in the plate, the slots at one side 40 being arranged between each pair of studs and with their front edges in a plane to the rear of the front edges of the said studs for the purposes specified.

4. A tie plate having upon its otherwise 45 upper plane face rail engaging studs at both ends, those at one end being arranged in pairs, said plate having longitudinally disposed tie engaging flanges on the under side that correspond in number with and are arranged in alinement with the rail engaging 50 studs, spike holes through the said plate, the holes at one side being disposed between each pair of rail studs, the said holes between each pair of rail studs having their front edges in 55 a plane to the rear of the front edges of the said studs, the latter being relatively so arranged as to wedge against the spike head when the latter is driven home between the said studs, the inner edges of the said studs 60 being tapered, all being arranged substantially as shown and described.

5. A tie plate consisting of a plane top member having a series of longitudinal pendent tapering flanges that extend from end to 65 end of the plate, spike openings in each end of the said plate, rail engaging studs arranged in pairs at one end of the plate, each pair of said studs straddling a spike opening, the bearing faces of said studs being in a plane 70 in advance of said spike openings, and the inner adjacent walls of the said studs being spaced away from the said openings and having their upper portions beveled.

WILLIAM J. WILLIAMS.
